UNITED STATES PATENT OFFICE

IRA D. FORD, OF ROSELAND, ONTARIO, CANADA, ASSIGNOR TO UNIVERSAL BUTTON FASTENING & BUTTON COMPANY, OF DETROIT, MICHIGAN, A CORPORATION OF MICHIGAN

BUTTON

Application filed September 18, 1929. Serial No. 393,328.

This invention relates to metal buttons and aims to provide an improved sheet metal button combining the neat and substantial appearance of the composition or pearl button with the strength and economy of manufacture of the metal button.

The nature of the invention may be readily understood by reference to one illustrative button embodying the invention and shown in the accompanying drawing.

In said drawing:

Fig. 1 is a sectional elevation of the button after the forming operations but before any finishing treatment.

Fig. 2 is a plan view of the button.

Fig. 3 is a section similar to Fig. 1, of a button provided with a protective or decorative coating.

Metal buttons have been largely used where utilitarian considerations, such as those of strength and ease of attachment, were controlling. The appearance of the typical button used on workingmen's clothing, et cetera, has interfered with the more extensive use of the metal button. The illustrative button while being made of very thin sheet metal (.010" to .012" thick) is shaped in such form that it gives the substantial appearance of the composition or pearl button, used on shirts for example, and yet is of such form that it may be satisfactorily subjected to all the usual finishing treatments for metal buttons, such as cleaning, plating, et cetera.

In the present instance the inventive features have been embodied in a sew-on button having four thread eyes 11. The metal of the button which, as stated above, may be from .010" to .012" thick, may advantageously be sheet aluminum appropriate for die forming operations. In forming the button the central portion thereof is depressed as at 12 to provide a recessed area to receive the exposed portions of the attaching thread extending between the thread holes 11, which portions therefore lie below the surface of the outer face 13 of the button and are protected from wear. The margins 14 of the button blank are rolled or curled around so as to provide an edge 15 which gives the ap-

pearance of substantial thickness to the button such as that of the typical pearl or composition shirt button. The extremity 16 of the button edge terminates a distance 17 from the central portion of the button to permit the rapid escape of any liquids such as cleaning solution or a plating acid which may enter during the cleaning or plating operations. Such solutions if retained in the button would obviously be liable to cause damage both to the button and to the clothing to which the button is attached. The space 17, therefore, should be wide enough so that capillary action cannot interfere with the escape of the liquid. The under edge 18 of the button rim should either be level or inclined slightly toward the center of the button so as not to form a pocket for the retention of cleaning liquids or plating acids.

Either a portion or all of the metal displaced by the thread holes 11 may be curled underneath the bottom of the button as at 19 and uniformly distributed around the hole to provide a marginal reinforcement therefor and a smooth and rounded exposed surface 20 for the thread holes which presents no sharp edges to cut the thread.

The thinness of the sheet metal not only reduces the cost of the button (without resulting in the flimsy appearance which might characterize a thin sheet metal button) but it permits of easy and simple forming operations. For example, there is no tendency of the metal to split or crack at the edge 16 because (owing to its thinness) excessive stresses do not develop in the die operations. It is, therefore, not necessary to curl the edge 16 under so as to conceal the ragged edge which might result from the use of thicker metal.

After the formation of the metal, the buttons are cleaned to remove the oil or grease customarily placed on the sheet metal to lubricate and reduce wear on the dies. Due to the formation of the button edge referred to above, the cleaning liquid readily escapes when the buttons are removed from the cleaning solution. The same applies to plating preparations or any other finishing or coat-

ing preparation which is subsequently placed on the button.

In Fig. 3 is illustrated in somewhat exaggerated form the tendency of the coating or surfacing 21 applied to the button, to obliterate as at 22 and 23 the evidence that the button is made merely from sheet metal and is not a solid button.

Obviously the invention is not limited to the details of the illustrative button since these may be variously modified.

Having described my invention, I claim:

1. As an article of manufacture, a sew-on button formed of relatively thin sheet metal having a centrally depressed thread receiving portion provided with thread holes, and having the metal of its margin turned over to simulate a thick button edge, the turned edge of said metal being substantially parallel with the button face and terminating a distance from said centrally depressed portion and leaving the hollow space of said button edge open for the free escape of liquids employed in connection with the finishing of said button.
2. As an article of manufacture, a sew-on button formed of relatively thin sheet metal having a centrally depressed thread receiving portion provided with thread holes, and having the metal of its margin turned over to simulate a thick button edge, the turned edge of said metal being substantially parallel with the button face and terminating a distance from said centrally depressed portion and leaving the hollow space of said button edge open for the free escape of liquids employed in connection with the finishing of said button, said distance being great enough to prevent capillary interference with the escape of said liquids.

In testimony whereof, I have signed my name to this specification.

IRA D. FORD.
